UNITED STATES PATENT OFFICE

173,032

AIRPLANE

Clarence L. Johnson, Encino, and Willis M. Hawkins, Jr., North Hollywood, Calif., assignors to Lockheed Aircraft Corporation, Burbank, Calif.

Application June 8, 1953, Serial No. 25,376

Term of patent 14 years

(Cl. D71—1)

To all whom it may concern:

Be it known that we, Clarence L. Johnson and Willis M. Hawkins, Jr., both citizens of the United States, residing at Encino and North Hollywood, respectively, in the State of California, have invented a new, original, and ornamental Design for an Airplane, of which the following is a specification, reference being had to the accompanying drawings, forming a part hereof.

Figure 1 is a side perspective view of an airplane showing our new design;

Figure 2 is a bottom perspective view thereof;

Figure 3 is a top plan view thereof;

Figure 4 is a side elevational view thereof;

Figure 5 is a front elevational view thereof; and

Figure 6 is a rear elevational view thereof.

The dominant features of our design reside in those portions shown by means of full lines. The landing gear has been omitted from Figures 1 and 2 for convenience of illustration.

We claim:

The ornamental design for an airplane, as shown and described.
